(57) **CLAIM**

The ornamental design for a vehicle body, as shown and described.

DESCRIPTION

FIG. 1 is a front, side and top perspective view of a vehicle body showing the new design; and

FIG. 2 is a rear, opposite side and top perspective view thereof.

FIG. 3 is a rear view thereof.

FIG. 4 is a front view thereof; and,

FIG. 5 is a left side view of the new design, the right side being a mirror image thereof.

In the drawing views, the tires, emblems, written matter and wheels shown in the broken lines are for illustrative purposes only and form no part of the claimed invention.
